Lester A. Dent, Richmond Annex, and Claire L.
Basford, Richmond, Calif.

Application August 5, 1952, Serial No. 20,914

Term of patent 14 years

(Cl. D29—1)

To all whom it may concern:

Be it known that we, Lester A. Dent, a citizen of the United States and a resident of Richmond Annex, county of Contra Costa, State of California, and Claire L. Basford, a citizen of the United States and a resident of Richmond, County of Contra Costa, State of California, have invented a new, original, and ornamental Design for a Wreath, of which the following is a specification, reference being had to the accompanying drawing, forming a part thereof.

Fig. 1 is a front elevational view of a wreath, showing our new design, and

Fig. 2 is a sectional view thereof, taken along the line 2—2 of Fig. 1.

We claim:

The ornamental design for a wreath, as shown.

LESTER A. DENT.

CLAIRe L. BASFORD.
